UNITED STATES PATENT OFFICE.

LÉON CRAYSSAC, OF CETTE, FRANCE.

PHOTOPRINTING FRAME FOR FILM NEGATIVES.

Original application filed August 17, 1922, Serial No. 582,522. Divided and this application filed May 9, 1923. Serial No. 637,923.

To all whom it may concern:

Be it known that I, LÉON CRAYSSAC, a citizen of the Republic of France, residing at 7 Rue de l'Esplanade, Cette, France, ⁵ have invented certain new and useful Improvements in Photoprinting Frames for Film Negatives, of which the following is a specification.

This application is a division of application Serial No. 582,522, filed August 17, 1922, now Patent No. 1,497,290, June 10, 1924, and the present invention relates to improvements in photo printing frames of the type having an automatic adjustment ¹⁰ and in which the device is provided with two sets of releasable grips for holding the negative and the positive in their exact respective positions during the printing operation. The apparatus is particularly adapt- ¹⁵ ed for use in printing of film negatives, but can also be used for printing plates, and the invention relates more particularly to an improvement in the apparatus de- ²⁰ scribed and illustrated in the said Patent No. 1,497,290.

The object of the present invention is to facilitate the printing of negatives when many copies of the same subject are to be obtained, all with a uniform margin on ³⁰ every side, quickly, without trouble and without the necessity of employing skilled operators.

With these objects in view and with other objects, which will appear as the ³⁵ specification proceeds the invention consists in the new features of construction and combination of parts hereinafter described and particularly pointed out in the claims.

In the drawings accompanying and forming ⁴⁰ part of the specification:

Fig. 1 is a plan view showing in full lines the prolongation of the knee lever shaft operating the set of grips holding the positive to be printed; a portion of the frame ⁴⁵ being shown in dotted lines.

Fig. 2 is a plan view drawn to a smaller scale—of the metal portion of a sizing diaphragm to be used when printing off plate negatives.

Fig. 3 is a plan view to the same scale as Fig. 2 showing the cardboard sheet which receives the plate negative.

Fig. 4 is a section on line 1—1 of Fig. 2, drawn to a slightly larger scale—showing ⁵⁰ the sizing diaphragm with its metal portion and cardboard sheet.

Fig. 5 is a cross section, to a larger scale showing a frame portion with the sheet of transparent material and its carrying springs. ⁶⁰

Fig. 6 shows in longitudinal section a part of the frame with groove, spring and sheet of transparent material.

Fig. 7 is a plan view of the frame showing in full lines the parts adapted to allow the ⁶⁵ passing of film negatives; the frame being shown diagrammatically in dotted lines.

Fig. 8 is a section on line 2—2 of Fig. 7 and to a larger scale showing the slot in the frame and the carved out portion of the ⁷⁰ U-shaped shutter allowing the passing through of film negatives.

Fig. 9 is a front view of one of the film negative adjusting devices disposed on the side of the frame. ⁷⁵

On the drawings the dotted lines indicate certain of the parts covered by the main patent above referred to and A is the frame; F the shutter hinged to the frame A by the hinges A'; and T is the abutment against ⁸⁰ which the folding portion of the shutter is engaged when in the open position.

As in the patent above referred to, the frame holds a transparent sheet and the holding means is hereinafter described. On ⁸⁵ the transparent sheet is placed a sizing diaphragm which, when used for printing plates is of a particular form as herein-
after described; and the diaphragm is held in position by means of a shutter rigid as a ⁹⁰ whole and hingedly connected at A' to the frame on the one side whilst on the opposite side it is kept in the closed position by means of locks, latches or the like engaging on the arm extremities of the U shaped ⁹⁵ shutter.

Upon the U shaped shutter are fixed and operate the knee lever shaft M connected to and operating the grips N, the shaft M being produced in M' so as to form a handle ¹⁰⁰ at its double bent end and the knee lever shaft K of the set of grips holding the negative. The handle M'' lies below lever R. On finishing one print, the two sets of grips may be automatically released by ¹⁰⁵ simply operating the lever R which in its displacement engages the handle M'' and moves the latter, thus disengaging at the same time the paper print and the negative. Finger rests X are provided at the extremities of each working lever so as to facilitate the application of the fingers upon each of ¹¹⁰

them, the levers are fitted with means for connecting them with balanced pedals, said pedals being adjustable so that they may be controlled by foot pressure.

5 The sizing diaphragm selected for the print to be obtained is placed on the transparent sheet B of the frame; this diaphragm consisting of a cardboard sheet *a* (Figs. 2, 3, and 4) cut out internally to the dimensions and shape corresponding as exactly as possible with the dimensions and shape of the photographic plate to be printed.

Over the cardboard sheet *a* is fixed by means of rivets *b* the metal sheet *c* which is 15 very thin; this metal sheet is cut in its central portion in any convenient shape, i. e. rectangular, three sides of the rectangle only being cut through so as to form a flap to permit the introduction of the negative 20 to be printed after slightly lifting said flap. The flap also has a central cut out portion, slightly smaller than the corresponding portion on the cardboard sheet; these openings correspond with each other and the difference 25 in their dimensions gives the margin surrounding the print.

A small semicircular opening *e* permits easy placing and removal of the photographic plate; for each size of plates a 30 special diaphragm is required.

To permit the use of same printing frame for printing positives off films or plates disposed in the sizing diaphragm, the transparent sheet B disposed in the interior and 35 at the bottom of the frame, rests upon the flat springs *f* which by their elasticity permit the adjustment of the sheet B according to the thickness of the diaphragm employed; such springs always exerting a 40 steady pressure against the foldable part of the shutter thus ensuring close contact between the plate or film and the printing paper.

The springs *f* are mounted and fixed in a 45 groove *g*, (Figs. 5 and 6) so that the upper portion of the spring is contained for one half of its width in the groove whilst the other half carries the transparent sheet on a corresponding width. The springs are 50 thus securely held in their normal position in the groove to which they are fixed and ensure on the other hand, by means of the protruding part of the upper bends the hold on the protruding transparent sheet 55 B. This transparent sheet is thus held along its four sides; its displacements are always parallel and occur without special strains for any thickness of the diaphragm actually in use.

60 To print from the film negatives shown in *h* in Figs. 7 and 8 slot shaped openings *i* are disposed horizontally on the sides of the frame A; one extremity (J Fig. 9) of each opening corresponding exactly to a 65 line parallel to the edge of the rigid shutter

and in prolongation of the set of grips *l*; these slots of a determined length are slightly wider in the interior of the framing so as to permit the easy passing through of the film *h* below the protruding arms of 70 the rigid portion of the shutter, said arms having been equally cut out to this purpose as shown in Fig. 8, so as to leave the film completely free to be placed under the foldable shutter I which during the printing 75 holds it in position relatively with the set of grips. Adjusting devices *l* (Fig. 9) are provided on the sides of the frame A, said devices partly covering the slots *i* so as to leave free only an opening corresponding 80 to the width of the film *h*; to this purpose the device *l* carries at right angles a small heel *m*, which engages the film *h* thus forcing it to enter the slot and always move parallelly to the printing opening D of diaphragm C. The screws *n* permit of the device being fixed after adjustment upon the frame A, and the extremities are bent as shown in *o*, *m* (Fig. 9) to allow for a free and easy movement in adjusting. This disposition makes it possible to print successively all the negatives of the film or only 85 a certain number of them, without the necessity of cutting the film.

Naturally the form, dimensions and materials may be varied according to requirements.

I declare that what I claim is:

1. A photo printing frame for film negatives comprising a frame, provided with 100 means to resiliently hold a transparent sheet disposed at its bottom; a sizing diaphragm cut out in its central portion; a rigid U shaped shutter hingedly connected on the one side to the frame, arm extremities on 105 the U shaped shutter, locking organs fixed on the opposite side of the frame and engaging upon the said arm extremities to retain the shutter in its closed position, a releasable spring controlled knee lever shaft 110 carried by the shutter, a set of grips to hold the negative in its adjusted position disposed in the thickness of the U shaped shutter, a set of grips traversing the thickness of the shutter and adapted to hold the positive in 115 its adjusted position, a releasable spring controlled knee lever shaft carrying the latter grips, a foldable shutter filling up the cut out portion between the arms of the U shaped shutter and hingedly connected to 120 it, a spring bar disposed on the arms of the U shaped shutter for keeping the said foldable shutter in its closed position, film guiding means on the framing and on the U shaped shutter, and a plurality of reference 125 marks disposed on the thickness of the U shaped shutter abutting with the said foldable shutter.

2. A photo printing frame for film negatives comprising a frame provided with 130

means to resiliently hold a transparent sheet disposed at its bottom, said means comprising a groove running along the inside and at the bottom of the frame, fixed bent blade 5 springs mounted in the groove and having a width equal to the width of the groove towards the bottom of the frame whilst on top of the groove the springs protrude sufficiently to receive and maintain the transparent sheet; a sizing diaphragm cut out in its central portion; a rigid U shaped shutter hingedly connected on the one side to the frame, locking means for retaining the U shaped shutter closed in its working position; arm extremities on the U shaped shutter adapted to be engaged by the said locking means and to allow the passage of a film negative, a releasable spring controlled knee device carried on the said shutter 10 and disposed in the thickness of the U shaped shutter to hold the negative in its adjusted position, a releasable spring controlled knee lever shaft, a set of grips carried by the latter shaft and traversing the thickness of the shutter to hold the positive in its adjusted position, a foldable shutter filling up the cut out portion between the arms of the U shaped shutter and hingedly connected to it, a spring bar disposed on the arms of the U shaped shutter to keep the foldable shutter in its closed position, and film guiding means on the framing and on the U shaped shutter.

3. A photo printing frame for film negatives comprising a frame provided with means to resiliently hold a transparent sheet

disposed at its bottom; a sizing diaphragm cut out in its central portion; a rigid U shaped shutter hingedly connected on the one side to the frame, arm extremities on 15 the U shaped shutter, locking organs carried on the frame and engaging upon the arm extremities of the U shaped shutter and adapted to allow the passage of film negatives, a releasable spring controlled knee lever shaft carried by said shutter, a set of grips provided on the said shaft and disposed in the thickness of the U shaped shutter to hold the negative in its adjusted position, a second releasable spring controlled 20 knee lever shaft, a set of grips provided on the latter shaft and traversing the thickness of the shutter, to hold the positive in its adjusted position, a foldable shutter filling up the cut out portion between the arms of the U shaped shutter and hingedly connected to it, a spring bar disposed on the arms of the U shaped shutter to retain the foldable shutter in its closed position, slots being provided on the opposite sides of the 25 frame and corresponding grooves being provided on the arms of the U shaped shutter and slidably and adjustably mounted controlling squares mounted upon the frame and adapted to engage the film edges; and a plurality of reference marks disposed on the thickness of the U shaped shutter abutting with the foldable shutter.

In testimony whereof I have hereunto affixed my signature.

LÉON CRAYSSAC.
